[57] CLAIM

The ornamental design for an automotive emergency tool, as shown and described.

DESCRIPTION

FIG. 1 is a perspective view of an automotive emergency tool showing my new design;

FIG. 2 is a top plan view thereof;

FIG. 3 is a front elevational view thereof;

FIG. 4 is a bottom plan view thereof;

FIG. 5 is a rear elevational view thereof;

FIG. 6 is a right-side elevational view thereof; and,

FIG. 7 is a left-side elevational view thereof.

The broken line showing of the ice scraper is for illustrative purposes only and forms no part of the claimed design.

FIG. 6

FIG. 7
